CLAIM

The ornamental design for a tank for garden sprayer, substantially as shown and described.

DESCRIPTION

FIG. 1 is a rear elevational view of a tank for garden sprayer showing my new design;

FIG. 2 is a front elevational view thereof;

FIG. 3 is a right side elevational view thereof;

FIG. 4 is a left side elevational view thereof;

FIG. 5 is a top plan view thereof; and

FIG. 6 is a fragmentary top perspective view thereof, with the handle shown in raised position, and with portions of the tank being omitted for ease of illustration. The bottom face of the handle is not ornamented.
